US00D747795S

(12) **United States Design Patent**
Blomberg et al.

(10) **Patent No.:** US D747,795 S
(45) **Date of Patent:** ** Jan. 19, 2016

(54) **RESPIRATOR MASK BODY**

(71) Applicant: **3M INNOVATIVE PROPERTIES COMPANY**, St. Paul, MN (US)

(72) Inventors: **David M. Blomberg**, Lino Lakes, MN (US); **Michael J. Cowell**, Woodbury, MN (US); **Carl W. Raines, III**, Woodbury, MN (US); **Mark W. Schulz**, Minneapolis, MN (US); **Charlie Wood**, Minneapolis, MN (US)

(73) Assignee: **3M Innovative Properties Company**, St. Paul, MN (US)

(**) Term: **14 Years**

(21) Appl. No.: **29/518,808**

(22) Filed: **Feb. 27, 2015**

(51) LOC (10) Cl. **29-02**

(52) U.S. Cl.

USPC **D24/110.1**

(58) **Field of Classification Search**

USPC D24/110.1-110.4, 110.6

CLAIM

The ornamental design for a respirator mask body, as shown and described.

DESCRIPTION

FIG. 1 is a perspective view showing the new design for a respirator mask body;

FIG. 2 is a front view thereof;

FIG. 3 is a rear view thereof;

FIG. 4 is a right side view thereof, the left side being a mirror image thereof;

FIG. 5 is a top view thereof; and,

FIG. 6 is a bottom view thereof.

The broken lines in the drawings illustrate portions of the respirator mask body which form no part of the claimed design.

1 Claim, 3 Drawing Sheets
